TRUNDLE TOY

Willis M. Lakin, Slinger, Wis., assignor to Marlin
Toy Products, Inc., Horicon, Wis., a corporation of Illinois

Filed Feb. 23, 1967, Ser. No. 5,913

Term of patent 14 years

(Cl. D34—15)

Fig. 1.

Fig. 2.

Fig. 3.

Fig. 4.

FIGURE 4 is a frontal perspective view thereof with the dotted line representation of the handle omitted for convenience of illustration.

The dominant features of my new design are shown in full lines.

I claim:

The ornamental design for a trundle toy, as shown and described.
